UNITED STATES PATENT OFFICE.

THOMAS MILLS, OF SANDHURST, ENGLAND.

PROPULSION OF VESSELS.

1,049,384.

Specification of Letters Patent.

Patented Jan. 7, 1913.

Application filed July 25, 1912. Serial No. 711,435.

To all whom it may concern:

Be it known that I, THOMAS MILLS, a subject of the King of Great Britain, residing at Longdown Lodge, Sandhurst, Berkshire, England, have invented new and useful Improvements in the Propulsion of Vessels, of which the following is a specification.

This invention relates to improvements in the propulsion of vessels such as are described in the specification of my prior Patent No. 457361. Such a vessel has a fore part of a curved conical form surrounded by a hollow conical propeller of corresponding form and adapted to revolve thereon and having blades projecting from its exterior.

The object of this invention is to lessen the friction of the conical propeller turning on the fore part, which friction is largely caused by the water entering the space between the propeller and fore part.

According to this invention I provide the conical propeller with two sets of internal blades, one set for expelling the water from this space when the vessel is being driven forward and the other when the vessel is being driven astern. I also provide a shield over the top of the propeller which prevents the water from flying upward and so aids the action of the propeller.

The drawings illustrate apparatus made in accordance with this invention.

Figure 1 is a side elevation, Fig. 2 a vertical section and Fig. 3 a transverse section on the line 3—3 Fig. 2.

a is the fore part of the vessel capable of turning upon which is a propeller b having external curved blades c and two sets of internal blades d and e. The set d

expels the water from the space f when the vessel is being driven forward while the set e comes into operation when the vessel is being driven astern. As the water is expelled from the space f air is admitted to it through the pipe g. A shield h secured by a stay i to a bearing on the propeller shaft j and by a stay k secured to the vessel, covers the top of the propeller.

What I claim is:

1. A vessel with the whole fore part of a stationary curved conical form, surrounded by a hollow conical propeller of corresponding form and adapted to revolve thereon and having blades projecting from its exterior and winding around it, and blades on its interior at the end adjacent to the vessel.

2. A vessel having at its front end a stationary conical portion a, in combination with a hollow conical propeller adapted to revolve about said portion a, having spirally arranged blades on its exterior and blades in its interior at the end adjacent to the vessel and provided with means for revolving it.

3. A vessel with the whole fore part of a stationary curved conical form, surrounded by a hollow conical propeller of corresponding form and adapted to revolve thereon and having blades projecting from its exterior and winding around it, and blades on its interior at the end adjacent to the vessel, and a shield at the top of the conical propeller.

THOMAS MILLS.
